UNITED STATES PATENT OFFICE.

GEORGE H. F. SCHRÄDER, OF NEW YORK, N. Y.

MACHINE FOR APPLYING FERRULES.

SPECIFICATION forming part of Letters Patent No. 741,073, dated October 13, 1903.

Application filed March 31, 1902. Serial No. 100,884. (No model)

To all whom it may concern:

Be it known that I, GEORGE H. F. SCHRÄDER, a citizen of the United States, residing in the city, county, and State of New York, have invented certain new and useful Improvements in Machines for Applying Ferrules, of which the following is a specification.

My invention aims to provide a machine for applying a ferrule to a compressible tube, such as the ordinary small rubber tube to which the valve of a pneumatic tire is fastened or such as the ordinary rubber or other hose to the end of which a nozzle or coupling is to be attached. The machine of the present application contains improvements in this class of machines generally and is specially adapted to carry out the process of applying ferrules described in my application for patent, Serial No. 100,339, filed March 27, 1902.

With this end in view my invention aims to provide a machine which may be cheaply constructed by means of which ferrules can be applied perfectly and expeditiously and which is easily adjusted to meet differing conditions as to diameter and length of ferrule.

My invention aims also to provide various improvements specified in detail hereinafter.

Referring to the accompanying drawings, illustrating an embodiment of my invention, Figure 1 is a longitudinal section of a complete apparatus, partly in elevation. Fig. 2 is a rear end view of the same. Fig. 3 is a front end view of the same. Fig. 4 is a view of a collet taken out of the shell. Fig. 5 illustrates the application of the apparatus to the applying of a ferrule to the valve-tube of a pneumatic tire. Fig. 6 is a section on the line 6 6 of Fig. 5.

My improved apparatus operates by compressing the ferrule upon the compressible tube, it being understood that the latter has in nearly all cases a rigid core therein which prevents collapsing of the tube. For example, in the case illustrated this core is formed by the metallic inner end of the valve-casing. In a hose the core would ordinarily be the inner portion of the nozzle or coupling-tube attached. The inward pressure is preferably produced by jaws which contract the ferrule radially and substantially equally at all points without corrugating it. Prefer-

ably a series of jaws is used, the pressing-faces of which are shaped to form, when they are pressed inwardly around the ferrule, a continuous pressing-face without corrugations. Preferably such jaws have tapered outer faces, which engage with the correspondingly-tapered inner face of a surrounding ring, so that when the jaws and ring are given a longitudinal movement relative to each other the jaws are pressed inwardly. I preferably use also in connection with means for contracting the ferrule a stop for determining the longitudinal position of the ferrule and tube relatively to the contracting means, the stop being preferably adjustable to fit it for operation under varying conditions.

Referring to the drawings, A represents a collet (shown separately in Fig. 4) and comprising, preferably, a ring B at one end and a series of jaw C, all of said parts being integral. The jaws C are thickened near their outer ends, where the greatest strain comes on them, and for carrying out the process of my aforesaid application are preferably provided with pressing-faces D of the shape illustrated and adapted when pressed inward, Fig. 6, to form a continuous pressing-face without corrugations. The entire collet is preferably made of a single piece of tempered tool-steel and with the jaws spread slightly apart, as indicated in Fig. 4. The outer faces E of the jaws C, near their ends, are tapered, as indicated, and are arranged for longitudinal reciprocation in a ring F, which has a correspondingly-tapered inner face surrounding the faces E of the jaws. A shell G receives the collet and in its outer enlarged end receives the ring F, the latter being preferably screwed therein, as shown. The shell is preferably provided with a standard H, integral therewith, by which it may be attached to a work-table or the like.

The means for giving the collet the necessary longitudinal movement to press the jaws inward and contract the ferrule consists of a shaft J, screwing into the shell G and bearing against the ring B of the collet, preferably through the intermediation of a ring K, which lessens the twisting tendency on the collet and reduces the wear on the same. As the shaft J is turned in one direction the

collet is pushed forward and the jaws are compressed, with the effect stated. As the shaft is turned backward the pressure on the jaws is released, and they are sufficiently 5 springy to expand slightly, at the same time moving backward in the shell, so as to permit the withdrawal of the ferruled tube.

For applying ferrules of different diameters the collet A may be removed and replaced by another of suitable size, the ring F being first removed. The turning of the shaft is effected, preferably, by means of a lever L, clamped on the rear portion thereof. The lever will ordinarily stand in the vertical position illustrated and will be pulled downward in the direction indicated by the arrow, Fig. 2, until the arm M thereon strikes a stop N, which is preferably a screw entering the outside of the shell G at a suitable 15 point. With collets of different proportions it is advisable to vary the position of the operating-shaft J relatively to the lever L, rather than make it necessary to turn the lever L to an inconvenient position in order to effect the 20 complete movement. For this purpose an adjustable connection is provided between the shaft and the lever, consisting, preferably, of a pin O in the hub of the lever, adapted to enter any one of a series of 25 apertures P in a flange Q on the screw-shaft. To effect the desired adjustment, the clamping-screw R is loosened and the lever L withdrawn longitudinally from the flange Q. Then holding the lever L in the position assumed at the end of its stroke, with the arm 30 M against the stop N, the shaft is turned by means of its knurled end S until the jaws C are brought to the desired final position. The lever L is then moved up against the 35 flange Q of the shaft, with its pin O in the nearest hole P, and the screw R tightened to clamp it.

A feature of the invention which is of use not only in connection with the specific 40 compressing means indicated, but with other types of compressing means, is a stop for determining the longitudinal position of the ferrule and tube relatively to the compressing means and which in the form illustrated is longitudinally adjustable. In the present case I have also shown this stop movable longitudinally and simultaneously with the compressing-jaws, so that a corresponding longitudinal movement is given to the tube and ferrule, 45 and these parts receive only an inward pressure from said jaws. This stop in the present case consists of a rod T, preferably having an enlarged head U and adapted to be adjustably attached to the shaft J to operate in the 50 manner described by having its rear portion passing through the shaft J and fixed in position therein by means of a set-screw V.

The operation of the device in applying a 55 ferrule to the valve-tube of a pneumatic tire is illustrated in Figs. 5 and 6, in which W is the valve-tube, of rubber, X is a portion of the valve-casing which is to be fastened into the

tube W, and Y is the ferrule, the outer edge of which is preferably turned inward, as shown, over the end of the tube and the inner edge of which is preferably slightly flared to avoid cutting the rubber, this flare being formed by a flare Z at the outer end of the jaws. In inserting the tube into the machine the rod T is first loosened by unscrewing the 70 set-screw V, and the tube is then pressed inward, the end of the valve member X bearing against the head U of the rod T and pushing the latter back until the ferrule is properly located within the jaws. The set-screw 75 V is then tightened to fix the position of the head U relatively to the jaws. The lever L is then pulled down, as explained, and the jaws, rod, tube, and ferrule are pushed forward simultaneously, the jaws being at the same time 80 pressed inward to contract the ferrule, as explained. After one adjustment of the rod T it of course remains fixed for subsequent operations upon duplicate tubes and serves to determine without any care on the part of 85 the operator when the tube is placed far enough into the machine.

Though I have described with great particularity of detail an apparatus embodying my invention, yet it will be understood that 90 the invention is not limited to the specific apparatus described. Various modifications and rearrangements of the parts are possible to those skilled in the art without departure from the invention. For example, although 95 my apparatus is designed to contract a ferrule without corrugating it, yet I have found in practice that, especially where the ferrule is too large for the tube, there is sometimes a slight fold in the metal after contraction. 100 This fold is slight and unintentional and is not a necessary incident of the operation of my machine; but it is to be understood, of course, that whether the machine operates perfectly as designed or imperfectly it is equally 105 within the broad invention.

What I claim is—

1. In an apparatus for radially contracting on a compressible tube at substantially all parts of its circumference a continuous cylindrical sheet-metal ferrule so as to convert it into a similar continuous cylindrical sheet-metal ferrule of smaller diameter, the combination of a series of jaws adapted to surround such ferrule, and means for pressing 115 said jaws inward to form a substantially continuous pressing-face around said ferrule whereby to contract said ferrule on the tube without corrugating it.

2. In an apparatus for applying a ferrule 120 to a compressible tube, the combination of a series of jaws adapted to surround such ferrule, means for pressing said jaws inward by a longitudinal movement thereof, and means for giving said tube and ferrule a longitudinal movement simultaneously with that of 125 said jaws so that they receive only an inward pressure from said jaws.

3. In an apparatus for applying a ferrule

- to a compressible tube, the combination of a series of jaws adapted to surround such ferrule and having inclined outer faces, a ring surrounding said jaws and having a correspondingly-inclined inner face, a screw-shaft 5 for giving said jaws a longitudinal movement in said ring whereby they are pressed inward, and a lever for rotating said screw-shaft.
4. In an apparatus for applying a ferrule to a compressible tube, the combination of a series of jaws adapted to surround such ferrule and having inclined outer faces, a ring surrounding said jaws and having a correspondingly-inclined inner face, a screw-shaft 10 for giving said jaws a longitudinal movement in said ring whereby they are pressed inward, a lever for rotating said screw-shaft, and means for connecting said lever adjustably to said shaft.
- 15 5. In an apparatus for applying a ferrule to a compressible tube, the combination of a collet consisting of a ring and a series of jaws, said jaws having inclined outer faces, a second ring adapted to surround said jaws and having a correspondingly-inclined inner face, a screw-shaft adapted to move said jaws longitudinally of said ring to press the same inward, and a shell carrying said collet, and carrying said screw-shaft at one end and said 20 second ring at the opposite end.
- 25 6. In an apparatus for applying a ferrule to a compressible tube, the combination of a collet consisting of a ring and a series of jaws, a screw-shaft for giving said collet a longitudinal movement, and a ring K interposed between said collet and screw-shaft.
- 30 7. In an apparatus for applying a ferrule to the outside of a compressible tube, the combination of means for contracting such ferrule on the tube, and a stop for determining the longitudinal position of the ferrule and tube relatively to said contracting means.
- 35 8. In an apparatus for applying a ferrule to a compressible tube, the combination of means for contracting such ferrule on the 40 tube, and an adjustable stop for determining the longitudinal position of the ferrule and tube relatively to said contracting means.
- 45 9. In an apparatus for applying a ferrule to a compressible tube, the combination of a series of jaws adapted to surround such ferrule, means for pressing said jaws inward by a longitudinal movement thereof, a longitudinally - movable shaft for producing said movement of the jaws, and a rod attached to 50 said shaft and movable therewith for giving said tube and ferrule a simultaneous longitudinal movement.
10. In an apparatus for applying a ferrule to a compressible tube, the combination of a series of jaws adapted to surround such ferrule, means for pressing said jaws inward by a longitudinal movement thereof, a longitudinally - movable shaft for producing said movement, and a rod connected to said shaft 55 and adjustable longitudinally thereof and adapted to give said tube and ferrule a longitudinal movement simultaneously with that of said jaws.
11. In an apparatus for radially contracting 60 on a compressible tube at substantially all parts of its circumference a continuous cylindrical sheet-metal ferrule without corrugating it so as to convert it into a similar continuous cylindrical sheet - metal ferrule of 65 smaller diameter, the combination with a collet consisting of a ring and a series of jaws having inside pressing-faces shaped to form, when pressed inward around said ferrule, a continuous pressing - face without corruga- 70 tions, of means for pressing said jaws inward around a ferrule.
- In witness whereof I have hereunto signed my name in the presence of two subscribing witnesses.
